CLAIM

The ornamental design for a spare tire mounting drawer, as shown and described.

DESCRIPTION

FIG. 1 is a top perspective view of a spare tire mounting drawer showing my new design;

FIG. 2 is a front elevational view thereof;

FIG. 3 is a top view thereof;

FIG. 4 is a right side view thereof;

FIG. 5 is a left side view thereof; and,

FIG. 6 is a bottom view thereof.

The broken lines showing a tire in FIG. 1 are for illustrative purposes only and forms no part of the claimed design.
